(Cl. D58—11)

To all whom it may concern:

Be it known that I, Jules Brodeur, a citizen of the United States, residing at New York, in the county of New York and State of New York, have invented a new, original, and ornamental Design for a Combined Bottle and Container Therefor or Similar Article, of which the following is a specification, reference being had to the accompanying drawing, forming part thereof.

In the drawing:

Fig. 1 is a front elevational view of a combined bottle and container therefor or similar article showing my new design;

Fig. 2 is a side elevational view;

Fig. 3 is a rear elevational view; and

Fig. 4 is a top plan view.

I claim:

The ornamental design for a combined bottle and container therefor or similar article, substantially as shown.

JULES BRODEUR.
